M. ALVAREZ

RAIL JOINT

Filed April 10, 1920

FIG. 3

FIG. 4

Inventor
M. Alvarez,
By A.R. Kerslake
Attorney

UNITED STATES PATENT OFFICE.

MIGUEL ALVAREZ, OF SANTIAGO, CHILE.

RAIL JOINT.

Application filed April 10, 1920. Serial No. 372,949.

To all whom it may concern:

Be it known that I, MIGUEL ALVAREZ, citizen of the Republic of Chile, and residing at Santiago, Chile, Avenida El Salvador No. 5 2059, have invented a new and useful Improvement in Rail Joints.

This invention refers to a new system for the joining of rails of tramcars and wagons, whose object is to eliminate the movement 10 of the rails at their joints, thus avoiding the troublesome blow to passengers and at the same time the damage that is caused to the rolling stock and the wear and tear of the rails.

15 This invention consists of boring the rails transversely at the ends of both and afterwards introducing a tightly fitting hard steel plug.

This system has been practically used and 20 it has been proved satisfactory, leaving intentionally the fish plate in a loose condition, having observed that the rails have had no relative movement whatever and entirely eliminating the blow on the passing of the cars.

The diameter of the plug may be varied according to the cargo and the normal use 25 of the top part of the rail, it being applicable both to the Phoenix and Vignol rail, and 30 where the rails are imbedded by pavement or soil.

Referring to the drawings, Fig. 1 shows the joining of the rails 1 and 2 with fish-plate 3 and bolts 4 placed. 5 is the plug in 35 its position. Fig. 2 shows an end view of the rail with the plug placed.

Fig. 3 is a side view of a modification which permits expansion and contraction of the rails.

40 Fig. 4 is an end view of the modified arrangement.

This invention is also applicable to railroads that are subject to a periodical expansion and contraction.

In this case the plug in the form of an 45 elongated key, is placed at certain distances which on being introduced on the corresponding slots in both rails, allow of a longitudinal movement of the rails.

The other joints are made up with the 50 common cylindrical plugs.

The distance between the elongated plugs is fixed according to the country and climate where this invention is to be applied.

I am not aware that prior to my invention, 55 tramcar rails have been joined according to my system, and therefore I claim:

1. In a rail joint, the combination with the ends of two rails arranged end to end and having heads provided with oppositely 60 disposed transversely arranged horizontal recesses extending inwardly from one side of the heads, of a solid bridge plug arranged in said recesses and designed to prevent relative vertical movement of the ends of the 65 rails.

2. In a rail joint, the combination with the ends of two standard rails arranged end to end and having heads provided with oppositely disposed transversely arranged horizontal recesses extending inwardly from one side of the heads to a point adjacent the transverse center of the heads, of a hard metal plug removably arranged in said recesses and designed to prevent relative vertical movement of the ends of the 75 rails.

In testimony whereof I have signed this specification this 9th day of March 1920.

MIGUEL ALVAREZ.
